ATTORNEY

UNITED STATES PATENT OFFICE

2,423,666

SKIRT

Nathaniel Tennens, London, England

Application July 24, 1944, Serial No. 546,273
In Great Britain July 23, 1943

4 Claims. (Cl. 2—221)

(Granted under the provisions of sec. 14, act of
March 2, 1927; 357 O. G. 5)

1

This invention relates to skirts, slacks and other nether garments and has in view to provide such garments with supporting and fastening means capable of adjustment to allow for variation as to the effective waist measurement, thereby, in the case of maternity wear, providing for gradual abdominal enlargement and subsequent contraction; a further object in the case of maternity wear being to provide at the front of the garment a supplementary supporting means for same which allows for such enlargement and contraction in a vertical direction and ensures that the abdomen is comfortably and properly covered at all times. Another object of the invention is to provide for improving the appearance of the figure.

According to the invention a skirt, slacks or other nether garment incorporates, in the region of the waist, a gusset provided with a series of fastener elements disposed in spaced-apart relation across the width of the gusset, and has an associated part adapted to be engaged at a free end thereof with any selected one of the fastener elements of the gusset, thereby to provide for variation in the effective waist measurement of the garment.

The term "gusset" used in this specification and in the appended claims implies a gusset formed by an inserted gusset-forming piece or by an integral triangular extension of one of the panels of the garment.

Conveniently, in carrying out the invention, the garment is provided with a pair of gussets each having a series of fastener elements as above set forth, and a supporting waist band secured intermediate its ends to the body of the garment and adapted to be engaged at its respective ends with any selected fastener elements of the different gussets. Preferably the gussets are situated at the respective sides of the garment.

In a preferred form of the invention especially applicable to maternity wear but nevertheless applicable generally, the waist band is arranged to extend across the front of the garment and is permanently secured thereto at spaced-apart portions and means is provided for connecting the free intermediate part of said waist band to the front of the body of the garment in order to provide additional support for said garment, said connecting and supporting means being of a form which provides for variation vertically as to the disposition of the free part of the waist band with respect to the garment. The said connecting and supporting means conveniently may comprise a series of fastener elements provided

2

on the body of the garment and a co-operating fastener element provided on the free intermediate part of the waist band.

The garment provided by the invention as above set forth is capable of being worn as an ordinary garment, the adjustment provided at the gusset or gussets enabling the waist measurement of the garment to be adapted to the size of the figure. For maternity wear, the enlargement of the figure is thus provided for as is also the post-natal contraction of the figure; the vertically-adjustable connection at the front provides for complete covering of the figure and comfortable fitting of the garment over the abdomen during such enlargement and contraction.

A skirt of convenient form in accordance with the invention and which is primarily intended for maternity wear, is illustrated in the accompanying drawings, wherein—

20 Figure 1 is a front view of the upper part of the skirt,

Figure 2 is a side view,

Figure 3 is a fragmentary view of the central front portion of the skirt, showing the waist band broken away for clearness, and

Figure 4 is a fragmentary rear perspective view.

The skirt illustrated is provided at each side with a gusset 10 formed, in the example shown, by inserting a triangular piece of material between two adjacent panels 11, 12, of the skirt, although alternatively it could be formed by providing one of the panels with an integral triangular extension stitched to the meeting edge of the adjacent panel.

35 Each gusset 10 extends from the region of the hips to the top edge of the garment, which latter is adapted to lie at the waist, and is provided with a series of fastener elements 13 disposed in horizontal spaced-apart relation across said gusset near its upper end. The garment is pro-

40 vided with a front waist band 14 which is secured to the body of said garment where indicated by references 15, extending freely of same across the centre of the front. The free end portions 16 of said waist band are provided each with a fastener element 17 adapted to be engaged with any selected one of the fastener elements 13 provided on the adjacent gusset 10. On the front of the

45 body of the garment there is or are provided one or more sets of supporting fastener elements 18, the one or each set consisting of a series of elements spaced-apart in a vertical line, and the waist band 14 is provided with a fastener element 50 (or elements) 19, adapted to be engaged with any

selected one of the said supporting fastener elements constituting a set.

The gusset fasteners 13 which co-operate with the free end portions 16 of the waist band allow a range of adjustment to accommodate variation in waist measurement, and the gusset itself enables the garment to adapt itself to variation of size in the region from the waist line to the hips whilst ensuring that the garment presents a neat appearance at all times. The vertical set (or sets) of fasteners 18 allows for raising of the free centre part of the waist band 14 with consequent paying out of the body of the garment as demanded by relatively greater measurement in the lower part of the abdomen. Thus, changes of body contour as regards expansion are allowed for whilst ensuring adequate covering for the abdomen and comfortable supporting of the garment at all times. Conversely, the waist measurement can be gradually decreased and the front of the garment taken up to allow for decrease of abdominal measurements during the post-natal period, these variations being made by the horizontal and vertical sets of fasteners aforesaid.

The fasteners employed for the horizontal and vertical sets may be of any suitable kind such as, for instance, a hook and loops, a press stud and sockets, or a button and button holes. In the example shown the elements 13 and 18 consist of loops and the elements 17 and 19 consist of hooks.

There may be only a single set of vertical fastener elements at the front centre, as shown, or there may be two, three or more parallel sets, all adapted to engage the free intermediate part of the waist band.

I claim:

1. A skirt having, in the region of the waist, a pair of gussets disposed at the respective sides of the skirt and each provided with a series of fastener elements disposed in spaced-apart relation across the width of the gusset, and having a supporting waist band secured near its respective ends to the body of the skirt, and arranged to extend across the front thereof, fastener elements provided on free end portions of said waist band for engagement with any selected fastener elements of the respective gussets, thereby to provide for variation in the effective waist measurement of the skirt, a series of fastener elements provided on the front of the body of the skirt and which are vertically spaced apart, and a co-operating fastener element on the free central part of the waist band for engagement with any selected one of the said vertically separated fastener elements to provide additional support for the skirt in a manner which allows for variation

vertically as to the disposition of the free central part of the waist band with respect to the body of the skirt.

2. A skirt having, in the region of the waist, means providing for variation as to the effective waist measurement of the skirt, and in combination therewith a waist belt arranged to extend across the front of the skirt and which is permanently secured thereto at spaced apart positions adjacent each end thereof, said belt being free along the part intermediate said permanently secured positions, and means for connecting the free intermediate part of said waist belt to the front of the body of the skirt in order to provide support therefor, said connecting means being of a form which provides for variation vertically as to the disposition of the free part of the waist belt with respect to the skirt.

3. A skirt according to claim 2, wherein the said connecting and supporting means at the front of the skirt comprises a series of fastener elements provided on the body of said skirt and a cooperating fastener element provided on the waist band.

4. A skirt having in the region of the waist a waist belt secured at spaced apart positions to the body of the skirt and having its intermediate portion free of said skirt body, means for supportably connecting the skirt body to the free intermediate part of the waist belt in a manner affording vertical adjustment as to the disposition of the waist belt with respect to the skirt body, gussets provided on the skirt body and situated in the proximity of the positions where the belt is fixed to said body, extensions to the belt beyond its said positions of fixing, and means for connecting said belt extensions to the skirt body in a manner affording adjustment as to the fullness of each gusset.

NATHANIEL TENNENS.
